UNITED STATES PATENT OFFICE

153,314

DESIGN FOR A HELICOPTER

Frank N. Piasecki, Lansdowne, Pa., assignor to
Piasecki Helicopter Corporation

Application March 13, 1947, Serial No. 137,601

Term of patent 14 years

(Cl. D71—1)

To all whom it may concern:

Be it known that I, Frank N. Piasecki, a citizen of the United States of America, residing at Lansdowne, in the county of Delaware and State of Pennsylvania, have invented a new, original, and ornamental Design for a Helicopter, of which the following is a specification, reference being had to the accompanying drawing, forming part thereof.

Figure 1 is the side elevational view of a helicopter, showing my new design as it would appear on the ground with the cargo doors shown in open position.

Figure 2 is a front elevational view of the same.

Figure 3 is a top plan view of the same.

Figure 4 is a perspective view of the same.

Figure 5 is a rear elevational view of the same.

I claim:

The ornamental design for a helicopter, as shown.

FRANK N. PIASECKI.
